UNITED STATES PATENT OFFICE.

JOHN C. JACKSON AND HENRY WHITCOMB, OF PHILADELPHIA, PENNSYLVANIA.

BELT-SHIFTER.

SPECIFICATION forming part of Letters Patent No. 430,345, dated June 17, 1890.

Application filed August 30, 1889. Serial No. 322,408. (No model.)

To all whom it may concern:

Be it known that we, JOHN C. JACKSON and HENRY WHITCOMB, citizens of the United States, residing at Philadelphia, in the county 5 of Philadelphia and State of Pennsylvania, have invented certain new and useful Improvements in Belt-Shifters; and we do hereby declare the following to be a full, clear, and exact description of the invention, such as 10 will enable others skilled in the art to which it appertains to make and use the same.

Our invention relates to those belt-shifters in which the belt is shifted upon a stationary holder instead of a loose pulley.

15 The object of our device is to provide a holder which will be capable of adjustment to any desired position in relation to the driven pulley; and a still further object of it is to provide means for shifting the belt with 20 greater facility.

With these purposes in view our invention consists in the peculiar features and combinations of parts more fully described herein-after, and pointed out in the claims.

25 Referring to the accompanying drawings, Figure 1 represents a front view of our invention as attached to a ceiling and in proximity to the driving-pulley. Fig. 2 is a side view of the same; Fig. 3, a view of the holder 30 when shifted to a different position from that in Fig. 2, and Fig. 4 a detached view of the holder-plate.

The reference-letter A denotes the bracket, which can be fastened to the ceiling or wall 35 *u'*, adjacent to the drive-shaft X, by bolts *a*, or other suitable means. This bracket is provided with a curved arm B, having an arc-shaped slot *b*. The drive-shaft X rotates in boxes Z upon the lower ends of hangers M.

40 The holder-plate C is adjustably secured to the bracket by means of the bolts *c*, which pass through the arc-shaped slot *b* and holes C' in said plate, said bolts being provided with nuts *c'*. This arrangement allows the

45 holder to be adjusted to various positions relative to the driven pulley, as shown in Fig. 3. The holder is composed of an arc-shaped plate C and a series of belt-receiving rollers E, mounted upon the bolts F, which 50 bolts pass through elongated radial slots G in the plate C. These elongated slots permit

the receiving-rollers to be adjusted toward and from the center of the bracket, whereby they can be made to conform to pulleys of various sizes.

55 The belt-shifting mechanism comprises the usual horizontal shifting-bar R, which may, for convenience, in the present instance, be mounted in boxes e on the ends of arms f and f', the latter being cast integral with the holder-bracket A. The bar is operated by the hand-lever P, which is provided with a pawl and ratchet *u t*. The ratchet *u* is secured to the ceiling *u'*. In order to assist in throwing the belt more quickly onto the driving-pulley, an arm Q is secured to the shifting-bar R and extends out opposite the pulley-bracket, and has upon its branches *q* the laterally-extending fingers *r* astride the belt. A coil-spring *s*, which encircles the bar R, is 60 provided to assist in more quickly throwing the belt from the rollers E onto the pulley W. 65

70 The preferred mode of constructing our device having been set forth we will now proceed to describe its operation.

75 The holder is secured to any suitable support in such position relative to the driving-pulley W and its shaft X that the belt Y can be as readily shifted as upon a loose pulley. When it is desired to stop the driven pulley, 80 the shifting-bar is drawn back by the lever P and the arm Q, and the fingers *r* take hold of the belt and throw it off onto the receiving-rollers E, whereupon the spring-pawl *t* will snap into the ratchet *u* and hold the hand-lever back against the tension of the retracting-spring *s*. In throwing the belt back upon the pulley the reverse operation is performed with the assistance of the retracting-spring. 85

90 It is evident that many slight changes which might suggest themselves to a skilled mechanic could be resorted to without departing from the spirit and scope of our invention; hence we do not limit ourselves to the precise construction shown.

95 What we claim as new, and desire to secure by Letters Patent, is—

1. In a belt-shifter, a bracket having an arc-shaped slot, a plate provided with a series of rollers or supports arranged in the arc of a circle, and means whereby the supports are adapted to be adjusted 100

- axis of said circle in the manner and for the purpose substantially as described.
2. In a belt-shifter, a bracket provided with an arc-shaped slot, in combination with a belt-holder having bolts passing through said slot and arranged to be moved therein, whereby the holder can be adjusted in the manner and for the purpose substantially as described.
- 5 3. In a belt-shifter, the combination of a bracket having an arc-shaped slot, a plate having bolts passing through and adjustably
- secured within said slot, said plate being provided with radial slots, and a series of rollers having bolts adjustably secured within the radial slots, all arranged and adapted to operate as described.
- 15 In testimony whereof we affix our signatures in presence of two witnesses.
- JOHN C. JACKSON.
HENRY WHITCOMB.
